[57] CLAIM

The ornamental design for a cake container, as shown and described.

DESCRIPTION

FIG. 1 is a perspective view of a cake container showing our new design;

FIG. 2 is a top plan view thereof;

FIG. 3 is a bottom plan view thereof;

FIG. 4 is a front elevational view thereof; the rear elevational view being a mirror image thereof; and,

FIG. 5 is a left side elevational view thereof; the right side elevational view being a mirror image thereof with the exception of the handle shown.
